DIESEL ENGINE COMPANY, OF ST. LOUIS, MISSOURI, A CORPORATION OF MISSOURI.

TWO-CYCLE INTERNAL-COMBUSTION ENGINE.

1,169,891.

Specification of Letters Patent.

Patented Feb. 1, 1916.

Application filed September 7, 1912. Serial No. 719,065.

To all whom it may concern:

Be it known that I, ARNOLD VON SCHMIDT, a subject of the Emperor of Germany, and resident of Munich, Germany, have invented a new and useful Improvement in Two-Cycle Internal-Combustion Engines, of which the following is a full, clear, and exact description, reference being had to the accompanying drawings, forming part of this specification.

The new arrangement of ports forming the object of my invention is illustrated in the accompanying drawings wherein—

Figures 1 and 2 show the arrangement for a double acting and Figs. 4 and 5 the arrangement for a single acting engine, the latter embodying a modification of my invention. Fig. 3 is a diagrammatic view illustrating a cross section through a cylinder in the zone of the inlet and exhaust ports. Fig. 1 is a longitudinal section through a cylinder on line $x-x$ of Fig. 3. Fig. 2 is a longitudinal section on line $y-y$ of Fig. 3. Figs. 6 and 7 are detail views showing modifications hereinafter more fully described.

My invention has relation to certain new and useful improvements in two-cycle internal combustion engines, and more particularly to means for providing an improved scavenging action.

Two-cycle internal combustion engines are known, in which the inlet ports for the air or charge are located in the same cylinder zone as the outlet ports. In some of these engines, the charge enters the cylinder on one side of the same, is diverted toward the cylinder head by a deflecting surface on the piston, drives the exhaust gases in front of it, along the head and the opposite cylinder wall, to the exhaust openings. In another type of such two-cycle engines, a plurality of streams of the charge, radially introduced, are directed toward the end of the cylinder by deflecting surfaces on the piston, the direction of said streams being reversed by the cylinder head, so that they are combined and flow back into the middle of the cylinder, driving the exhaust gases before them throughout their entire travel. In still other two-cycle engines, in which the charge is also introduced on one side of the

cylinder, they are not forced against the cylinder head by means of deflecting surfaces, but by the direction of some of the inlet slots, which are turned away from the outlet slots, so that the exhaust gases are also driven in front of the charge along the cylinder head and walls to the outlet slots. It is characteristic of all these methods of scavenging that the incoming charge drives the exhaust gas in front of it, and in its own direction of movement. This principle of scavenging is based upon the fact that the scavenging air must travel through a long path back and forth in the cylinder and along the cylinder head and must therefore change its direction several times.

Scavenging by means of deflecting ribs or deflecting surfaces formed on the piston, is particularly not suitable for Diesel motors, because in so doing, isolated air pockets are formed in which the fuel cannot enter in its central injection, and also because in Diesel motors, the compression chamber is so small that the said pockets alone would be too large, and finally because the compression chamber of the Diesel motor must have a definite form, which cannot be obstructed by recesses, deflecting ribs or special forms of the piston and head. According to the present invention, this old principle of scavenging is abandoned, and a new principle substituted, in which the exhaust gases are not driven in front of the fresh charge and the consequent long travel and frequent change of direction, is done away with. Instead of this, a new arrangement of the slots is employed, whereby the interior of the cylinder is divided into several scavenging regions by a plurality of inlet slots inclined obliquely toward the cylinder end, each of said regions being provided with one or more outlet openings, so that always two scavenging streams drive the exhaust gas, lying between them, from two sides toward the outlet openings. As the free air jets spread out perpendicularly to their own direction, two adjacent scavenging streams or jets act to compress the quantity of burnt gas lying between them and thereby force it out through the proper outlet for this particular region. This fundamentally new arrangement is particularly adapted for those motors which

scavenge only with fresh air, and is consequently especially suitable for Diesel motors. However, with a carefully separated sequence of scavenging air and charge, it can also be employed in explosion motors.

In the drawings, *a* is the cylinder with a stuffing box *f* and exhaust ports *d*.

b is the piston with its hollow piston rod *c*. In Fig. 2 the piston is near the upper dead-point having compressed the combustion air. At this moment the fuel valve *g* is opened by the cam shaft *m* and the fuel is injected in the hot combustion air. The fuel being ignited drives the piston downward and opens first the exhaust ports *d*. When the pressure of the combustion gases is diminished nearly to atmospheric pressure, then the piston opens the inlet ports *e*.

Fig. 3 is a diagram of the new method of scavenging. The scavenging air produced in a known manner by a scavenging pump enters through a number of scavenging openings, *e e*, directed obliquely toward the cylinder end (see Figs. 1 and 2). Each two adjacent streams or collection of streams can spread out on all sides normally to their direction (see the small arrows in the elevation and plan), since they flow freely through the cylinder space in consequence of their oblique direction. They consequently drive the exhaust gases, lying between them, out through the exhaust openings *d*, *d* which are suitably located within this region. As the air currents expand freely on all sides and flow at an acute angle against each other they lose their velocity and spread out at the cylinder end, whence the filling of the cylinder with fresh air proceeds equally to the outlet openings.

The number of the subdivisions of the cylinder space into scavenging regions, can be either great or small, the minimum being two such regions (see, for example, Figs. 4 and 5). The number of the subdivisions depends upon the dimensions of the cylinder, the number of revolutions and the speed of the piston; that is to say, according to the necessary speed of the scavenging, since a small region is scavenged in much shorter time than a large region. Finally the subdivision depends also upon the required completeness of the scavenging and consequently of the combustion. It will be seen from Fig. 3, that by the spreading of the scavenging currents on all sides, the exhaust gases lying between the same and the cylinder wall are crowded out and forced to escape from said region by the nearest exhaust opening.

It is entirely immaterial whether the directions of the scavenging streams, entering obliquely to the cylinder axis, cut each other at a point of the cylinder axis inside or outside the cylinder, in other words, form a cone, or whether individual streams meet each other at points, lying outside the cylinder axis, or are inclined obliquely to each other (as in Figs. 4 and 5). It is also immaterial whether the outlet ports lie in approximately the same cylinder zone as the inlet ports, as in Figs. 1 and 2, or whether they are placed somewhat higher. The charge or scavenging streams may be introduced as a whole, as shown in the upper half of Fig. 3, or they may be broken up by bars or partitions, as shown in the lower half of said figure, so that they do not enter as solid streams, but as bundles of streams. In order not to affect the direction of the incoming scavenging streams, the edge of the piston may be beveled or recessed as shown at *b*¹ in Figs. 6 and 7. This, however, does not change the principle of the scavenging operation.

Since the air currents, in consequence of their oblique direction relatively to the cylinder axis, penetrate into the midst of the exhaust gases, and consequently present to them as large a surface of contact as possible, the exhaust gases in consequence of this intensive cooling effect of the scavenging air, contract suddenly to a fraction of their original volume, and are completely driven out of the cylinder by the scavenging air expanding normally to the direction of its flow. The subsequent filling of the cylinder with a fresh charge is more compact than with the methods of scavenging above mentioned, since the scavenging streams do not flow along hot metal parts (such as deflecting ribs or baffles and cylinder walls) from which they take up heat. Furthermore the new method of scavenging presents the advantage that the scavenging streams, without first having their force diminished by deflecting ribs and long travel with several changes of direction, are conducted in the shortest path and without encountering any obstructions, to the cylinder head, where the fuel enters and where, consequently, a complete cleaning out of the exhaust gases is most important. This new scavenging principle is particularly advantageous for large cylinder dimensions, in which the old scavenging methods above mentioned diminish the force of the scavenging streams, in consequence of the more than twice as long path of travel and of the numerous changes of direction. The employment of this method of scavenging is also very advantageous in double acting internal combustion engines, particularly for double acting Diesel motors, the scavenging of which by means of the methods referred to, acting on one side only was not possible, because the intervening piston rod caused the scavenging air or charge to be stowed, diverted and set into whirls. It will be seen from Figs. 2 and 3 that the piston rod does not stand in the way of the complete operation of this new method, but on the contrary

serves to limit the separate regions and to prevent a whirling of the streams from one region into another.

Instead of the arrangement shown in Fig. 5 1, with common charging slots for both sides of the cylinder, a small bar *h* (see Fig. 2 left side) may be provided for the better guiding of the piston, between the upper and lower guiding surfaces of the charge 10 slots; or instead of one common charge port, two separated ports *i k* may be provided (see Fig. 2, right side).

In the embodiment of the invention shown in Figs. 4 and 5, the cylinder zone, containing the scavenging and exhaust slots, is only divided into two scavenging regions, and in such a way, that each two exhaust openings *d*, and each two scavenging openings *e* lie opposite each other. The latter 20 are, similarly to the scavenging slots shown in the lower half of Fig. 3, divided into a number of smaller slots *r*. There is consequently formed a bundle of streams in each of the two scavenging regions. These 25 bundles of the two opposite scavenging openings *e*, crowd the exhaust gases in the region lying between them to the two exhaust openings from both sides. By this construction, the two parts of the cylinder 30 periphery, provided for the scavenging regions, are so large that they can be subdivided into a large number of slots *r*, whereby another marked advantage is obtained. Thus some of the said slots, as 35 those at one side, can be so placed that they are not only inclined toward the cylinder head, but so that they are also directed in pairs toward each other. In this way, the two oppositely lying bundles of streams are 40 given a tendency to form a wall, which divides the cylinder space into two parts. The scavenging action is the same as in Figs. 1-3, so that here also the scavenging streams compress the exhaust gases between 45 them. This particular manner of dividing and directing the air streams has for result, that the charge is massed in the central region of the cylinder space and particularly near the cylinder head, whereby a very 50 full charge of the cylinder is obtained. It is possible to direct the scavenging slots more or less directly toward each other than is represented in the drawing. The less 55 they are inclined toward each other, the less will be the massing of the charge.

I claim:

1. A two-cycle internal combustion engine having a cylinder whose side walls are provided with a plurality of inlet ports and also with a plurality of exhaust ports arranged intermediately of the inlet ports, the inlet ports having oblique walls to direct scavenging streams entering the cylinder through said ports inwardly and also toward an end 60 of the cylinder so as to crowd out the ex-

haust gases through the exhaust ports, substantially as described.

2. A double-acting two-cycle internal combustion engine having a cylinder whose side walls are provided with a plurality of 70 inlet ports and also with a plurality of exhaust ports, arranged intermediately of the inlet ports, the inlet ports having oblique walls to direct the entering scavenging streams inwardly and also toward both ends 75 of the cylinder so as to crowd out the exhaust gases through the exhaust ports, substantially as described.

3. A two-cycle internal combustion engine, having a cylinder provided with two 80 inlet ports opposite to each other, each of which is divided into a number of smaller ports which are inclined both to the end of the cylinder and to each other.

4. A double-acting two-cycle internal 85 combustion engine having a cylinder whose side walls are provided with a plurality of inlet ports and also with a plurality of exhaust ports, arranged intermediately of the inlet ports, the latter having separate discharge openings directed obliquely toward the respective ends of the cylinder so as to 90 crowd out the exhaust gases through the exhaust ports, substantially as described.

5. A two-cycle internal combustion engine 95 having a cylinder whose side walls are provided with a plurality of inlet ports and also with a plurality of exhaust ports arranged intermediately of the inlet ports, the inlet ports having oblique walls to direct 100 scavenging streams entering the cylinder therethrough inwardly and also toward the ends of the cylinder so as to crowd out the exhaust gases through the exhaust ports, and each inlet port being divided into a plurality of separate discharge passages to 105 break up the scavenging streams into a plurality of finer streams, substantially as described.

6. A two-cycle internal combustion engine 110 having a cylinder whose side walls are provided with a plurality of inlet ports and also with a plurality of exhaust ports arranged intermediately of the inlet ports, the inlet ports having oblique walls to direct scavenging 115 streams entering the cylinder therethrough inwardly and also toward the ends of the cylinder, and each inlet port being divided into a plurality of separate discharge passages to break up the scavenging 120 streams into a plurality of finer streams, and some of the inlet passages of each group being inclined reversely to others of the group, substantially as described.

7. A two-cycle internal combustion engine 125 having a cylinder whose side walls are provided with a plurality of inlet ports and also with a plurality of exhaust ports arranged intermediately of the inlet ports, the inlet ports having oblique walls to direct 130

scavenging streams entering the cylinder through said ports inwardly and also toward an end of the cylinder so as to crowd out the exhaust gases through the exhaust ports, together with a cylinder piston controlling said inlet and exhaust ports, the piston having an unobstructed end surface, substantially as described.

8. A two-cycle internal combustion engine having a cylinder whose side walls are provided with a plurality of inlet ports and also with a plurality of exhaust ports arranged intermediately of the inlet ports, the inlet ports having oblique walls to direct scavenging streams entering the cylinder through said ports inwardly and also toward an end of the cylinder so as to crowd out the exhaust gases through the exhaust ports, together with a cylinder piston controlling said inlet and exhaust ports, the

piston having an unobstructed and peripherally beveled end surface, substantially as described.

9. A two-cycle internal combustion engine having its cylinder provided with a series of alternately located inlet and exhaust ports, the inlet ports having inclined walls which cause the scavenging currents entering through these ports to converge inwardly and also toward an end of the cylinder to thereby divide the body of gases to be scavenged and crowd them toward the respective exhaust ports, substantially as described.

In testimony whereof, I have hereunto set my hand.

ARNOLD VON SCHMIDT.
